UNITED STATES PATENT OFFICE.

HENRY KROPP BENTE, OF SEDALIA, MISSOURI, ASSIGNOR OF THIRTY-THREE ONE-HUNDREDTHS TO JOHN L. GUERRANT, SIXTEEN AND ONE-HALF ONE-HUNDREDTHS TO EDWARD D. BOSSERMAN, AND SIXTEEN AND ONE-HALF ONE-HUNDREDTHS TO MELVILLE T. HENDERSON, ALL OF SEDALIA, MISSOURI.

POST.

1,210,372.

Specification of Letters Patent. Patented Dec. 26, 1916.

Application filed January 4, 1916. Serial No. 70,208.

To all whom it may concern:

Be it known that I, HENRY KROPP BENTE, a citizen of the United States, residing at Sedalia, in the county of Pettis and State 5 of Missouri, have invented a new and useful Post, of which the following is a specification.

The device forming the subject matter of this application is adapted to be employed as a fence post, and for any and all 10 purposes for which a strong, substantial, simply constructed metal post may be demanded.

The invention aims to provide a post 15 which may be fashioned at trifling expense out of metal, the post possessing unusual strength, with a minimum amount of metal.

It is within the province of the disclosure to improve generally and to enhance the 20 utility of devices of that type to which the present invention appertains.

With the above and other objects in view which will appear as the description proceeds, the invention resides in the combination 25 and arrangement of parts and in the details of construction hereinafter described and claimed, it being understood that changes in the precise embodiment of the invention herein disclosed can be made within 30 the scope of what is claimed, without departing from the spirit of the invention.

In the accompanying drawing:—Figure 1 shows in side elevation, one form of post constructed in accordance with the present 35 invention, sundry of the wire securing elements being omitted in the figure, in order that the staple receiving holes in the post may be more clearly disclosed; Fig. 2 is a cross section on the line 2—2 of Fig. 1; Fig. 40 3 is an elevation showing a modified form of the invention; Fig. 4 is a cross section on the line 4—4 of Fig. 3; Fig. 5 is a cross section similar to Fig. 4, but showing a slight modification in the invention; Fig. 6 is a 45 fragmental perspective of the structure shown in Fig. 5.

In carrying out the invention, as shown in Figs. 1 and 2 there is provided a metal post 1 adapted to serve as a fence post. The 50 post 1 comprises a pair of Z members denoted generally by the numeral 2, each Z member 2 including a body 3, a main flange 4 and an auxiliary flange 5, the flanges 4

and 5 projecting in opposite directions, and being connected with opposed, longitudinal, 55 vertical edges of the body 3. The flanges 4 of the Z members 2 are overlapped upon each other as shown in Fig. 2 and are connected by rivets 6 or other securing elements adapted to a like end. The outer longitudinal edges of the auxiliary flanges 5 are supplied with longitudinal ribs 7. Adjacent the point of union between the auxiliary flanges 5 and the body portions 3 of the Z members 2, the auxiliary flanges 5 are provided with longitudinally extended ribs 8. The outer edges of the main flanges 4 are equipped with longitudinal ribs 9, the inner edges of the main flanges 4 being equipped with longitudinal ribs 10, the ribs 9 being 70 concaved so that the ribs 10 may fit thereto, as clearly shown in Fig. 2 of the drawings. In the main flanges 4 of the Z members 2, registering openings 12 are provided, the openings 12 being diminished in width 75 adjacent their ends.

A fence wire 14 may coöperate with auxiliary flanges 5, a fence wire 15 coöperating with the overlapped main flanges 4, all as clearly shown in Fig. 2. Either of the wires 80 14 or 15 may be dispensed with if desired, or both the wires may be used together as shown in Fig. 2. The wire 14 coöperates with the ribs 7 and 8, the wire 15 coöperating with the ribs 9. Washers may bear 85 against the flanges 5, similar washers coacting with the innermost main flange 4 of the post, as shown in Fig. 2. The washers may be of rectangular outline as shown at 16 in Fig. 1, or they may be of circular outline, as shown at 17 in the said figure. The washers, whatever be their form, are provided with openings 18 through which are passed the legs of a staple 19, the bend of the staple engaging the wire 14 or the wire 90 15. The legs of the staples 19 are twisted together as shown at 20, to engage the washers. By means of the twisted staples 19, the wire may be kinked as shown at 20 and enter the ends of the openings 12 or, if 100 desired, the wire may run straight from one longitudinal rib to the other as indicated at 22.

From the foregoing description it will be obvious that the post forming the subject matter of this application comprises a 105

trough-shaped central portion provided along its longitudinal edges with oppositely projecting, parallel flanges disposed substantially at right angles to the side walls of the central portion.

As shown in Fig. 4 of the drawing, the fence post 23 comprises a trough-shaped central portion 24 having oppositely projecting flanges 25 provided with ribs 26 corresponding to the ribs 7 and 8. A wire 27 extends across the ribs 26 and may be kinked between the ribs of the respective flanges as shown at 28, the wire being engaged by twisted staples 29 passing through restricted openings 30 in the flanges 25 and coating with washers 31 of the type hereinbefore described. In this form of the invention, the post 23 is a one-piece structure, and is not built up out of two Z members, as shown in Fig. 2.

In Fig. 5 of the drawings, the post is a one-piece structure like the form shown in Fig. 4, and includes a trough-shaped body 32 provided with ribs 33 corresponding to the ribs 9 and 10, the post comprising oppositely projecting flanges 34, equipped with ribs 35 corresponding to the ribs 7 and 8. The essential difference between the form shown in Fig. 5 and the form shown in Fig. 4 resides in the fact that the form shown in Fig. 5 is provided with ribs 33.

As shown in Fig. 6, the post embodies a trough-shaped central portion 36 having oppositely projecting flanges 41 provided with ribs 37, corresponding to the ribs 8 in Fig. 2, the flanges 41 being provided with ribs 38 corresponding to the ribs 7 of Fig. 2. The flanges 41 may have tongues 39 struck therefrom and adapted to be bent either upwardly or downwardly to engage with the wire 40, the latter coating with the ribs 37 and 38. In this connection it is to be understood that the tongues 39 and the washers 16-17 and the twisted staples 19 may be used interchangeably on all forms of the invention wherein a wire holding means is required.

Having thus described the invention, what is claimed is:—

1. A metal post including a trough-shaped body comprising an intermediate portion and side walls projecting in a common direction from the intermediate portion, the longitudinal edges of the side walls being provided with oppositely extended

flanges disposed approximately parallel to the intermediate portion, the flanges being dished longitudinally toward the intermediate portion to form outstanding ribs adjacent the free longitudinal edges of the flanges, and to form outstanding ribs at the places of juncture between the flanges and the side walls.

2. A metal post including a trough-shaped body comprising an intermediate portion and side walls projecting in a common direction from the intermediate portion, the longitudinal edges of the side walls being provided with oppositely extended flanges disposed approximately parallel to the intermediate portion, the intermediate portion and the flanges being dished longitudinally toward each other to form outstanding ribs adjacent the free longitudinal edges of the flanges, to form outstanding ribs at the places of juncture between the flanges and the side walls, and to form outstanding ribs at the places of juncture between the side walls and the intermediate portion.

3. A metal post made up of two Z-members including flanges which are overlapped to cause the post to comprise a trough-shaped body and oppositely projecting flanges on the longitudinal edges of the body; and means for uniting the overlapped flanges.

4. A metal post including a trough-shaped body and oppositely projecting flanges at the free edges of the body, the post being made up of a pair of Z-members having overlapped flanges provided with openings; and a wire holding means located in the openings.

5. A metal post including a trough-shaped body and oppositely projecting flanges at the longitudinal edges of the body, the post being made up of a pair of Z-members having overlapped flanges, the overlapped flanges being provided along their longitudinal edges with inter-engaged longitudinal ribs; and means for uniting the overlapped flanges of the Z-members.

In testimony that I claim the foregoing as my own, I have hereto affixed my signature in the presence of two witnesses.

HENRY KROPP BENTE.
